UNITED STATES PATENT OFFICE.

JAMES H. WILSON, OF CHICAGO, ILLINOIS.

COLLAPSIBLE BOX.

987,206.

Specification of Letters Patent. Patented Mar. 21, 1911.

Application filed March 16, 1908. Serial No. 421,484.

To all whom it may concern:

Be it known that I, JAMES H. WILSON, a citizen of the United States, residing at Chicago, in the county of Cook and State of Illinois, have invented certain new and useful improvements in collapsible boxes in which the side members are preferably made of sheet metal and the end members of wood or strong light material.

10 The salient object of the invention is to provide a collapsible jacket or box adapted to inclose and protect a liquid can or the like, which is usually made of relatively weak material, from injury in shipping or handling.

Other objects of the invention are to provide a box, the sides and salient angles of which are reinforced in order to protect the box itself against injury and at the same time afford maximum strength and rigidity to the structure as a whole; to provide a relatively light and economical construction which can be packed* and shipped flat in a compact package, and which can be quickly assembled without necessitating the crimping or bending together of any of the various parts, and without the use of separate fastening devices; to provide a construction in which the side bodies are rigidly locked together when assembled by means of a novel and simple slip-joint connection; to provide a construction in which the panel like side bodies may be shaped by a single operation of the forming die, and in which the blanks are so cut as to permit the formation of rabbet like seats for the end members and one or more vertically strengthening ribs without necessitating any drawing of the metal; to provide a construction in which the various supporting and connecting parts are so arranged as to also act as reinforcing members and in general to provide an improved construction of the character referred to.

45 The invention consists in the matters hereinafter described and more particularly pointed out in the appended claims; and will be understood from the following description, reference being had to the accompanying drawings in which—

50 Figure 1 is a perspective view of the device as assembled. Fig. 2 is a transverse sectional view taken through the side walls of the view shown in Fig. 1. Fig. 3 is a plan view of the blank from which the side bodies are formed and showing the manner

of cutting the upper and lower edges of the blank to permit the formation of a reinforcing rib. Fig. 4 is an inside side elevation of one of the side bodies formed from the blank shown in Fig. 3.

Referring to the drawings 1—1' designate the respective pairs of side members, and 2—2 the respective end members which when assembled together form the complete box. These side members are preferably made of sheet metal and are detachably united to each other by means of a novel slip-joint connection. To this end the side members 1 have their respective vertical edges bent outwardly at an angle of approximately 45 degrees to the face of the side body, to form tongues 4. These tongues are adapted to have telescopic or slip-joint engagement with correspondingly inclined channel like or grooved members 5 formed by doubling and folding back the vertical edges of the members 1'.

In order to prevent the tongues 4 from slipping laterally out of the channel shaped locking members 5, the latter are provided along the line of juncture with the main body with vertically extending shoulders 6 which abut against corresponding parts of the tongues 4. The arrangement is such that these shoulders not only prevent the tongues from being forced laterally inwardly and out of the channel members, but they also increase the rigidity of the structure as a whole. The manner of forming these various interlocking parts will hereinafter be described. In this connection however it is to be noted that the interlocking of the tongues 4 with the channel members 5 not only serves to securely lock the side walls of the box together, but also form rigid rib like reinforcements which effectually protect the corners of the box against blows or other injuries.

Describing now the manner of fitting the end members 2 to the side bodies, the latter are provided at their respective upper and lower edges with rabbet like extensions 8, each rabbet comprising a horizontally extending shoulder 9 and a vertically disposed confining flange 10. As seen clearly in Fig. 1, the end members 2 rest upon the several shoulders 9 and are secured to the side bodies by means of small nails or brads 11 driven through the confining flanges 10. For a purpose hereinafter described the rabbet like extensions 8 are vertically and horizontally

divided so as to over-lap each other in their central portions as seen clearly in Fig. 1.

In order to reinforce the central portions of the side bodies, each is provided with a vertically disposed V-shaped rib 12 which is struck up from the main portion of the side body itself. To enable these ribs to be formed upon the side bodies in such manner that they will extend from one off-set or 10 rabbet to the other and thus not only stiffen the side body, but also support said off-set rabbets, the side body blank is cut through along a line coincident with the inner bending line or angle of the rabbet at each end 15 of the rib-forming portion, as indicated at *a*, and an intersecting cut *b* leads from each cut *a* out to the margin of the blank. The striking up of the rib has the effect of decreasing the width of the side body over all, 20 and this narrowing causes the margins thereof to over-lap at the cuts *b*, which, except for said cuts, would have to buckle up.

The rabbet like seats 8 are formed by bending the upper and lower tongues 13 25 outwardly at right angles along the dotted lines *c*—*c* and then bending them vertically upwardly along the dotted lines *d*—*d*. The channel like locking members 5 are formed by first bending the side tongues 13 outwardly at right angles along the dotted lines *e* to form the shoulder 6, thence bending the 30 tongues still farther outwardly along the dotted lines *f* at an angle of about 45 degrees and then folding the tongues back 35 upon themselves along the dotted lines *g*. The tongues 4 for the side bodies 1 are of course formed in a substantially similar manner.

From the foregoing it will be seen that 40 the various locking and reinforcing parts of the side bodies may be readily made from a simple rectangular cut blank.

In assembling the structure, the tongues 4 of the side members 1 are first slipped into 45 the respective channel like sockets 5 of the side bodies 1 and the end members seated in the respective rabbets 8. The latter may then be secured to the side bodies by means of small nails as heretofore referred to.

50 While my device is particularly useful as a protecting jacket for liquid receptacles it is of course not necessarily confined to such use. Its capability of being collapsed may be disregarded and the several members 55 united to each other permanently in the first instance.

While I have herein shown a preferred embodiment of the invention, in its broader aspects the invention is not confined to the 60 exact details of construction shown.

I claim as my invention:

1. In a box, a sheet metal wall having a rib bent up from and extending across the intermediate portion of said wall, and terminating inside the margins of the latter, 65 the ends of said rib being severed from the margin of the wall by transversely extending cuts, and said end margins being severed opposite the ends of said rib and having said severed portions over-lapping. 70

2. In a box, a sheet metal wall provided along two of its opposed margins with laterally off-set portions, a rib bent up from and extending across the intermediate portions of said wall and terminating inside the margins of the latter, the ends of said ribs being severed from the margins of the wall by transversely extending cuts, and abutting said off-set portions, the off-set marginal portions adjacent to the ends of said rib 80 being severed by a vertically extending cut, and said severed portions over-lapped. 85

3. In a box, a sheet metal wall provided along one of its marginal edges with a laterally off-set portion, a rib bent up from and 90 extending across the said wall and terminating inside the off-set margin of the latter, the end of said rib adjacent said off-set portion being severed from the main body of the wall by a transversely extending cut, the off-set marginal portion being severed by a vertically extending cut adjacent the abutting end of said rib, and said severed portions over-lapped. 95

4. In a box, a sheet metal wall provided along one of its margins with a laterally off-set portion, a rib bent up from and extending across the face of said wall, that end of said rib which is adjacent to said off-set portion being severed from the main body of the wall by a transversely extending cut, and said off-set marginal portion being likewise severed adjacent to the rib, and said severed portions over-lapped. 100

5. In a box, end members and paneled side walls, one or more rib like reinforcements formed on the respective faces of said side walls, rabbet like seats upon the respective upper and lower edges of said walls adapted to support and confine said end members, the ends of said ribs being severed from the body of the wall and abutting said rabbet like seats, and the marginal edges of said side walls being severed and over-lapped. 105

JAMES H. WILSON.
